United States Patent Office

Des. 194,109
Patented Nov. 20, 1962

194,109

BIRD FEEDER OR SIMILAR ARTICLE

William Dilley, 6039 Ridgebury Blvd.,
Mayfield Village, Ohio

Filed Jan. 16, 1961, Ser. No. 63,573

Term of patent 14 years

(Cl. D31—2)

Fig. 1

Fig. 2

FIG. 1 is a top perspective view taken from an end and one side of a bird feeder or similar article, showing my new design;

FIG. 2 is an end elevational view thereof;

FIG. 3 is a side elevational view thereof; and

FIG. 4 is a top plan view thereof.

The dominant features of my design reside in the portions shown in full lines.

I claim:

The ornamental design for a bird feeder or similar article, as shown and described.
